UNITED STATES PATENT OFFICE.

FRANK M. SALMON, OF WAVERLY, MISSOURI.

ORCHARD-HEATER.

1,104,832.

Specification of Letters Patent. Patented July 28, 1914.

Application filed October 29, 1913. Serial No. 798,127.

To all whom it may concern:

Be it known that I, FRANK M. SALMON, a citizen of the United States, residing at Waverly, in the county of Lafayette and State of Missouri, have invented certain new and useful Improvements in Orchard-Heaters, which the following is a specification, reference being had to the accompanying drawings.

10 This invention relates to new and useful improvements in heaters and more particularly to orchard heaters, the object of the invention being to provide an orchard heater of novel construction whereby heat may be produced and maintained in orchards and gardens which are sensitive and occasionally exposed to frost.

Another object of the invention is the provision of an orchard heater of the above character which will possess advantages in points of efficiency and durability, is inexpensive of manufacture and at the same time is simple in construction and operation.

With the above and other objects in view, the invention consists in the novel features of construction and the combination and arrangement of parts to be hereinafter more fully described, pointed out in the claim and shown in the accompanying drawings, in which—

Figure 1 is a side elevation of an orchard heater constructed in accordance with my invention. Fig. 2 is an enlarged front elevation illustrating the tank and one of the burners in its operative position. Fig. 3 is a detail perspective view of the angular plate; Fig. 4 is a top plan view of the receptacle and the plate in position; and Fig. 5 is a transverse sectional view of the receptacle, the plate being shown in its position.

Referring more particularly to the drawings, 1 indicates a storage tank which may be arranged in any suitable place within the garden or orchard and is adapted to contain a supply of liquid fuel such as oil, gasolene, or the like, said tank being constructed of sheet metal and provided at its upper end with a suitable opening normally closed by means of a cover 2 whereby the tank may be readily filled when desired. The tank 1 is mounted upon a suitable standard which comprises the upright posts 3 and the bottom portion 4 supported by said posts.

Extending throughout the orchard or garden I provide a feed pipe 5 which is preferably the main pipe and is connected

to the supply tank by means of the pipe 6. Arranged at intervals along the main supply pipe 5 are a plurality of connecting members 7 whereby the several faucets 8 are connected with the main supply pipe 5 to supply liquid fuel to the various burners arranged along the main supply pipe.

The burners arranged along the main pipe 5 are preferably in the form of substantially rectangular receptacles 9 having handle members 10 to support the receptacles and which are adapted to engage the hooks 11 which are suspended from the main pipe 5 so as to support the receptacles beneath the pipe. Arranged within each of the receptacles is an angular plate 12, the vertically disposed portion of which is provided at its lower longitudinal edge with a plurality of notches 13 which are arranged adjacent the bottom of the receptacle and allow the superfluous oil to flow back of the vertical portion. As illustrated in Fig. 5, the plate is arranged within the receptacle so that the oil from the faucet 8 will strike upon the horizontal portion and run over the edge into the receptacle.

It will be noted that at each end of the main supply pipe 5, I provide the upwardly projecting air inlet pipes 14 which supply air to the main pipe 5, so that the oil will flow freely therethrough. The main supply pipe 5 is suitably supported in position by means of the standards 15 which rest upon the ground and are provided upon their upper ends with suitable supporting portions 16 adapted to receive the main supply pipe and retain the same in position.

In the practical operation of my improved orchard heater, it will be readily apparent that when it is desired to start the fire at night, the faucets 8 are opened permitting a suitable amount of oil to flow into the receptacles 9. The oil in the bottom of the receptacle will be lighted and as the same burns, it will heat the plate 12 and the oil flowing from the faucet on to the heated plate 12 will be partially generated into gas, the generated portion of the oil readily burning and the heat therefrom passing into the air. It will be apparent that the superfluous oil which is not generated will pass from the angular edge of the plate in the receptacle where it is burned to maintain the plate in a heated condition.

From the above description taken in connection with the accompanying drawings, it

will be readily apparent that I have provided a simple and durable orchard heater of novel construction whereby heat may be produced and maintained in orchards and gardens at comparatively low cost. It will be understood that the oil may flow freely through the faucets but it will only be necessary to furnish enough oil to keep a continuous fire within the receptacles 9. It will be understood that when the device is not in use, the receptacles 9 may be quickly and readily removed from the main pipe 5, the main pipe 5 being also arranged so as to be quickly removed from the supply tank 1 when not in use.

While I have shown and described the preferred form of my invention, it will be obvious that various changes in the details of construction and in the proportions may be resorted to for successfully carrying my invention into practice without sacrificing

any of the novel features or departing from the scope of the appended claim.

What I claim is:—

In a device of the class described, a rectangular receptacle open at its upper end, and an angular plate within said receptacle, one portion of said plate arranged in an inclined position and spaced from the upper edge of one side wall of the receptacle, the remaining portion of said plate being arranged in a vertical position and having its lower edge resting upon the bottom of the receptacle and provided with spaced notches, as and for the purpose set forth. 35

In testimony whereof I hereunto affix my signature in the presence of two witnesses.

FRANK M. SALMON.
